UNITED STATES PATENT OFFICE

PAUL SCHLACK, OF BERLIN-KARLSHORST, GERMANY, ASSIGNOR TO ACETA G. M. B. H.,
OF BERLIN-LICHTENBERG, GERMANY, A CORPORATION OF GERMANY

MANUFACTURE OF ARTIFICIAL THREADS

Application filed March 1, 1928, Serial No. 258,430, and in Germany March 3, 1927.

The present invention relates to improvements in the manufacture of artificial silk threads by the dry spinning process.

In the manufacture of artificial silk by the dry spinning process the operation is generally such that the several threads after leaving the nozzles are drawn downwards against a current of warm air which enters into the spinning cells at the bottom there-
of and leaves at the upper part laden with vapor of solvent.

The use of the counter-current in drying the threads favors a gradual controlled solidification of the threads, a condition which is of the greatest importance for the properties of the thread. Practically, the suction of the air upwards has the great disadvantage that irregular currents of air are apt to occur in the spinning chamber where-
by the progress of the spinning is unfavorably affected.

These air currents are so much more injurious as they appear more strongly just in the most sensitive place of the formed fibers, namely at the suction-opening in the neighborhood of the nozzle so that they easily cause disturbances at the nozzle, the adhesion of separate threads to each other and the formation of faults in the product.

These disadvantages are the more apparent when the partitions forming the several chambers are perforated with the object of equalizing injurious differences of temperature and content of vapor of solvent within the several cells of the group constituting the chamber.

According to the present invention, the spinning can be considerably improved by subdividing each of the spinning cells by a constriction at a suitable level in the cell, so that there are formed two cells, both of which are connected at the upper end in controllable manner and independently of each other with the suction pipe, the movement of air being so adjusted that a more or less large part of the warmed air introduced from below and containing more or less vapor of solvent, if the known circulation is used, is withdrawn from the lower cell so that a comparatively small volume of

air laden with vapor of solvent is led through the higher subdivision. The subdivision of the spinning cells may be effected advantageously by movable flaps arranged to form a sort of funnel, so that it is possible to widen the passage for the thread during spinning without damaging the thread.

The invention insures that there is only an extremely slight and very uniform movement of air in the upper part of the spinning cell and that the several spinning cells may be put into communication with each other for the purpose of equalizing differences of temperature and content of vapor of solvent without objection. It is unimportant whether both parts of the subdivided cell are thus put into communication with adjacent cells or only the upper part; it is in the latter that the physical conditions are of first importance for the properties of the finished fiber.

A special advantage of this mode of operating is that even on opening the upper and lower doors of the spinning chamber neither the spinning operation in the cells in question nor the use of the perforated chamber walls of the neighboring cells is markedly affected, especially when the lower cells are separated from each other by walls which are not perforated; this advantage does not exist in the known arrangement.

Finally, the subdivision of the cells allows for varying the heating in the two parts independently of each other, which is of importance when silk of different titer is to be produced by one and the same machine, in which case one must operate under otherwise similar conditions with different quantities of air.

The annexed diagrammatic drawings represent an apparatus for carrying out our invention. In these drawings Fig. 1 is an elevation of an individual cell;

Fig. 2 is an elevation in cross-section of a number of cells arranged in series so as to form a single operating unit;

Fig. 3 is a plan view on an enlarged scale of the arrangement of flaps employed for subdividing the cell into two compartments.

In these drawings, *a* represents the upper compartment divided from the lower compartment *b* by flaps *d*, turning on hinges *c*; the opening and the closing of the flaps is effected by any suitable known device, which, however, is omitted for the sake of clearness. The filament is extruded through nozzle *e* and after passing through the compartments *a* and *b* is withdrawn from the cell below the lid *f₂* over a thread guide *n*; the upper lid *f₁* is provided so as to render the nozzle *e* easily accessible; *g* and *h* are independent-
ly regulated heating systems for the cell compartments *a* and *b*; the air necessary for drying the filaments enters at *i*. The major portion is withdrawn at *k* in the neighborhood of the funnel-like aperture formed by the flaps *d*, whereas the remainder is withdrawn at *l* near the nozzle *e*. In Fig. 2 the partitions *m* between the individual cells effectively prevent circulation of the drying medium in the lower part of the cells, i. e. between the individual compartments *b*. In the upper compartments *a* the partitions *m* are perforated over their whole length so as to allow of a thorough equalization of difference arising in the physical conditions of the atmosphere contained in the individual cells. In Fig. 3, *o* denotes levers which actuate the flaps *d*.

What I claim is:

1. In a dry spinning process for the manufacture of artificial silk threads, in which the drying is effected by an ascending current of a gaseous medium in counter-current to the silk filaments issuing from the nozzle, the steps consisting in withdrawing one part of said drying medium at a medium level of its path of contact with the filaments and the other part in proximity to the point of issue of said filaments from the nozzle.

2. In a dry spinning process for the manufacture of artificial silk threads, in which the drying is effected by an ascending current of a gaseous medium in counter-current to the silk filaments issuing from the nozzle, the steps consisting in withdrawing the greater part of said drying medium at a medium level of its path of contact with the filaments and the other part in proximity to the point of issue of said filaments from the nozzle.

3. A cell for the manufacture of artificial silk threads by the dry spinning process in which the drying is effected by an ascending current of a gaseous medium in counter-current to the silk filaments, comprising a constriction of the drying cell at a medium level of said cell, forming two compartments within said cell, means for withdrawing one part of the drying medium at the upper end of the lower compartment and means for withdrawing another part of said medium from the upper compartment in proximity to the point of issue of the filaments from the nozzle.

4. A cell according to claim 3 in which the constriction is formed by flaps capable of turning on hinges and arranged so as to constitute a funnel-like adjustable aperture.

5. Apparatus for the manufacture of artificial silk consisting of a plurality of cells according to claim 3 arranged in series, and means provided in the walls common to the upper compartments of adjacent cells for communication between said upper compartments.

6. Apparatus for the manufacture of artificial silk consisting of a plurality of cells according to claim 3 arranged in series, and perforations provided in the walls common to the upper compartments of adjacent cells for communication between said upper compartments.

7. Apparatus for the manufacture of artificial silk consisting of a plurality of cells according to claim 3 arranged in series, means provided in the walls common to the upper compartments of adjacent cells for communication between said upper compartments and means for heating the upper compartments independently of the lower compartments of said cells.

In testimony whereof, I affix my signature.

PAUL SCHLACK.
